UNITED STATES PATENT OFFICE.

HENRY NORMAN LEASK, OF MANCHESTER, ENGLAND.

CHARGING-DOOR FOR REFUSE-DESTRUCTORS AND OTHER FURNACES.

965,718.

Specification of Letters Patent. Patented July 26, 1910.

Application filed April 24, 1909. Serial No. 491,989.

To all whom it may concern:

Be it known that I, HENRY NORMAN LEASK, a British subject, residing at Manchester, county of Lancaster, England, have 5 invented certain new and useful Improvements in and Relating to Charging-Doors for Refuse-Destructors and other Furnaces, of which the following is a specification.

This invention relates to charging doors 10 for refuse destructors and other furnaces which are charged from above and is designed to provide a door of simple construction and one which cannot get out of order.

It consists essentially in mounting or supporting the door on cranks carried by a carriage, which cranks rotate with the carriage wheels, so that when the carriage is moved from the closed position of the door, the door is lifted by the cranks and carried 20 along—in a cycloidal curve—out of the closed position into the open one.

The invention will be fully described with reference to the accompanying drawings which show its application to a refuse de- 25 structor.

Figure 1. is a sectional elevation showing the door open, in the charging position. Fig. 2. is a similar view showing the door closed. Fig. 3. is a section on line $x-x$ 30 Fig. 2. Fig. 4. is an end view showing the parts in the position for charging.

The furnace A may be of any suitable or ordinary construction provided with an opening B at the top or summit of the furnace through which the furnace is charged. 35 The hopper or chute C containing the charge or through which it is fed to the furnace and which may be a fixture or movable is arranged over the charging opening, space 40 being allowed between the opening B and the chute C to allow of the passage of a truck or carriage D. Rails or runways E are placed upon the top of the furnace upon which the truck or carriage D runs.

45 The rails or runways E preferably consist of racks as shown in the drawings the wheels of the truck or carriage D being formed with teeth, so that the carriage cannot run irregularly and so that the door which is 50 hung from the wheels as described below when closed may be always deposited in its correct place.

The carriage D is preferably of frame construction and the wheels F are mounted independently of one another inside their bearings G on independent short axles g only

sufficiently long to carry the wheels F so that the whole of the space between the wheels is quite clear.

The door H for closing the opening B of 60 the furnace is carried by cranks J mounted on the inner side of the wheels F, preferably as near their periphery as possible, in such a manner that when the carriage is moved and the wheels rotated the door is moved 65 in a cycloidal curve. The position of the wheels F and door H is so arranged that the door normally closes the opening B as shown in Fig. 2, so that when the carriage is moved away the door is lifted from the 70 opening and carried away therefrom into the position shown in Fig. 1, leaving the opening free for charging.

If desired the rails or runways for the carriage D may be arranged above the top 75 of the furnace in which case the door H may be swung from the cranks J by means of links. In this case the wheels may be arranged on the outer side of the bearings G if desired and the cranks J on the outer side of 80 the wheels.

Instead of complete wheels half wheels or sectors may be employed for the carriage.

When a fixed fuel container or hopper is employed the carriage preferably carries a 85 second door or plate M on the upper side which normally closes or forms the bottom of the fuel container so that when it is withdrawn the fuel in the container is allowed to fall into the furnace.

The carriage D also carries a chute L which is moved into position over the furnace opening B, when the door is opened, to receive and direct the charge into the furnace, as it falls from the chute or hopper C. 95 One side N of the chute L is hinged at O to the side of the container or hopper C which normally is pushed to one side by the carriage but when the carriage is withdrawn and the door opened the side falls into 100 operative position to direct the material as the hopper C opens.

A catch may be provided on the carriage which engages a bar, snug or the like attached to the pivoted side to prevent it being knocked or jerked back by the falling fuel.

As shown in the drawings the side N is formed with one or more short arms P which move therewith on the hinge O and 110 the carriage carries an arm or arms P' adapted, just after the side N drops, to engage

with a runner or runners *p* on the arm or arms *P* to retain the side in its depending position and prevent it flying back under any jerk or concussion.

5. What I claim as my invention and desire to protect by Letters Patent is:—

1. In a device of the class set forth, the combination with a furnace having an upper opening, of a carriage shiftable over the 10 said opening and provided with a chute having a movable end which is automatically elevated and depressed relatively to the furnace opening as the carriage is moved in opposite directions, and a hopper under 15 which the carriage and chute have movement.

2. In a closing device for furnaces and the like, the combination with a furnace having a top opening, of a carriage shiftable over 20 said opening in opposite directions and having a door movably supported thereby and operating to open and close the said furnace opening, the carriage also being provided with a chute to aline with the furnace opening, and a hopper fixed above the furnace opening, the carriage and chute means being 25 movable between the bottom of the hopper and the opening and the chute means of the carriage operating to continue the hopper downwardly to the furnace opening.

3. In a closing device for furnaces and the like, the combination with a furnace having a top opening, of a carriage shiftable in opposite directions over the top of the 30 furnace and having a door suspended therefrom and automatically elevated and depressed by the shifting movement of the carriage to open and close the said furnace opening, and a hopper disposed above the top 35 opening of the furnace, the carriage being movable between the hopper and the top opening of the furnace.

4. In a closing device for furnaces and the like, the combination with a furnace having 40 an opening, of a carriage shiftable in opposite directions over the opening of the furnace and carrying a door which is automatically elevated and depressed by the shifting movement of the carriage in opposite 45 directions to open and close the furnace opening, the carriage also being provided with a chute to aline with the furnace opening, and a hopper disposed in fixed position above the furnace opening, the carriage 50 and chute being movable between the hopper and the furnace opening.

5. In a closing device for furnaces and the like, the combination with a furnace having an opening, of a carriage shiftable in opposite 55 directions over the opening of the furnace and having a door to open and close the said furnace opening in accordance with the movement of the carriage, the carriage also provided with a chute having a movable end which is automatically ele-

vated and depressed relatively to the furnace opening as the carriage is moved in opposite directions, and a hopper arranged in co-operative relation to the furnace opening, the carriage, chute and door being movable 70 between the hopper and the furnace opening.

6. In a closing device for furnaces and the like, the combination with a furnace having an opening and a supply means at a distance above and co-operating with said opening, of upper and lower doors mounted between the supply means and the furnace opening and having a traveling movement in reverse directions to respectively shut off and liberate the contents of the supply 80 means and to close and clear the opening of the furnace, the lower door having a rising and falling movement.

7. In a closing device for furnaces and the like, the combination with a furnace having 85 an inlet opening and a fuel supply means disposed in co-operative relation to said opening, of a carriage movable between the said inlet opening and the fuel supply means and carrying means for opening and closing the 90 fuel supply means and furnace opening, and a chute carried by and movable with the carriage, said chute being provided with a hinged end which is closed by the movement of the carriage to assist in directing the fuel 95 into the furnace opening from the supply means.

8. In a closing device for furnaces and the like, the combination with a furnace having an inlet opening and a fuel supply disposed 100 at a distance above the opening, of a carriage shiftable between the fuel supply and furnace opening and having upper and lower doors respectively operating to open 105 and close the fuel supply and inlet opening of the furnace, the lower door having a rising and falling movement, and a chute movable with the carriage between the inlet opening of the furnace and the fuel supply and beneath the latter to direct the fuel into 110 the furnace.

9. In a closing device for furnaces and the like, the combination with a furnace having an inlet opening and a fuel supply disposed at a distance from the said opening, of a 115 traveling carriage having a chute movable therewith between the fuel supply and inlet opening of the furnace, the chute having one end movably supported and closed by the movement of the carriage, and means co-operating with the said movable chute end for holding the same down in fixed position when closed.

10. In a closing device for furnaces and the like, the combination with a furnace 125 having an inlet opening and a fixed fuel supply disposed in co-operative relation to said opening, of a carriage movable between the said fuel supply and inlet opening and provided with upper and lower doors to re- 130

spectively open and close the fuel supply and inlet opening, and a chute having one side in the form of a movable door and the remaining sides fixed in relation to each other, the movable side of the chute being closed by the movement of the carriage and the chute complete forming a continuation of the fixed fuel supply to direct the fuel into the furnace when the doors of the car-

riage coöperating with the fuel supply and 10 furnace inlet are shifted to open position.

In testimony whereof I have hereunto set my hand in presence of two subscribing witnesses.
